tion of Illinois

Application November 28, 1947, Serial No. 788,765

6 Claims. (Cl. 250—20)

1

The present invention is directed to self-quench superregenerative receivers adapted for operation in the saturation-level mode and, particularly, to such receivers having operating characteristics which are stabilized with respect to variations of the operating conditions to which they are normally subjected in operation.

Superregenerative receivers of both the separately quenched and the self-quench type have found wide utility due to their exceedingly high sensitivity, extreme simplicity and inexpensive construction. The operating characteristics of many such receivers may, however, become quite unstable with variations of the operating conditions to which they are normally subjected in operation. For example, the variations of the value of the conductance of the resonant input circuit of the superregenerative receiver due to antenna loading thereof, changes in the value of the receiver circuit components due to aging, changes of the transconductance of the regenerator tube over the operating life thereof, variations of the energization of the receiver circuit, and tuning of the receiver from one wave-signal station to another having different wave-signal intensities may materially alter the operating characteristics of the superregenerative receiver.

Superregenerative receivers of the separately quenched type and characterized by relatively high stability of their operating characteristics have been proposed to avoid some of the foregoing difficulties. One such receiver employs a time-constant network in the input circuit of the regenerator tube thereof for developing therein a bias potential which is adapted to maintain the average anode-current pulse width substantially constant with variations of operating conditions to which the separately quenched superregenerative receiver is subjected. For some purposes, however, for example those applications wherein it is advantageous to effect a saving in the number of electron tubes and other electrical components, it is desirable to employ a self-quench superregenerative receiver yet it is usually further desirable that the receiver have high stability of its operating characteristics with respect to changes in the operating conditions experienced thereby. It may also be desirable that a receiver of this type exhibit certain other particular characteristics, such as controlled selectivity independent of the quench rate, which is not inherent in the usual self-quench superregenerative receiver. These requirements are difficult to obtain in a self-quench superregenerative receiver for reasons which will be stated hereinafter.

2

In a separately quenched superregenerative receiver, the selectivity is ordinarily governed by the wave form of the quench voltage applied thereto and particularly by the wave form in the vicinity of maximum sensitivity. The desired wave form may usually be secured by suitable design and adjustment of the quench-voltage generator. A self-quench superregenerative receiver develops its own quench voltage, however, and the attainment of a quench voltage having a particular wave form is considerably more difficult in this type of receiver. Any selection or adjustment of its circuit parameters to provide the desired quench-voltage wave form may considerably influence or modify the self-quench frequency in a manner which tends to impair the stability or modulation handling capacity of the receiver. Thus the design of a self-quench superregenerative receiver having high stability of its operating characteristics over a wide range of variation of operating conditions presents a rather unusual problem.

Superregenerative receivers, of both the separately quenched and self-quench types, characterized by high stability of the operating characteristics thereof over a wide range of variations of operating conditions are disclosed and claimed in the copending application of Bernard D. Loughlin, Serial No. 753,236, filed June 7, 1947, entitled "Superregenerative Receiver" and assigned to the same assignee as the present invention. The superregenerative circuits of these receivers employ a regenerator tube having a time-constant network degeneratively included in a circuit portion common to the input and output circuits of the tube. This network is effective in the self-quench type of circuit, for example, to maintain the average self-quench periodicity of the superregenerative receiver substantially constant. It does this by developing from variations of the anode current of the regenerator tube a control effect which maintains the average anode current of the regenerator tube substantially constant with variations of normal operating conditions. While excellent stabilizing action of a self-quench superregenerative receiver may be obtained in this manner, it has been determined that stabilization may not be quite as effective as desired under some rather severe operating conditions such as those imposed by a high quench rate or a low anode-supply voltage. This is partly due to the wave form of the individual periodic pulses of anode current which develop the control effect and provide the stabilizing action for the self-quench superregenerative

receiver. Each of the anode-current pulses comprises two portions. The first portion has a relatively low amplitude and usually a substantial duration and occurs during the oscillatory build-up interval, while the second portion has a considerably greater amplitude and ordinarily a much shorter duration and occurs during the saturation-level interval. The integrated values of these two portions determine the average value of anode current for any given value of self-quench frequency. If the two portions retain their wave shape with variation of the self-quench frequency, then it is apparent that the average anode current varies only with the number of anode-current pulses per second and thus only with the self-quench frequency. It has been determined in practice that when the quench frequency tends to change due to vary wide variations of the operating conditions of the self-quench superregenerative receiver, the low amplitude-long duration portion of each anode-current pulse may vary both in amplitude and duration. Accordingly, under some severe operating conditions this variation of the shape or area of the first portion of each anode-current pulse may represent a considerable part of the total value of each anode-current pulse. Hence, in spite of changes in the quench frequency, the average value of the anode current of the regenerator tube of the receiver may not tend to change sufficiently with the changes experienced in the operating conditions to develop the necessary control effect across the degenerative time-constant network for maintaining the average self-quench periodicity of the superregenerative receiver substantially constant.

The previously described arrangement of Bernard D. Loughlin, which derives its stabilizing action from the anode-current pulses flowing through the regenerator tube, includes an impedance in the anode-energizing circuit which reduces the voltage applied between the anode and the cathode of the tube. In special applications which require a high quench rate or which have available only a low-voltage anode-energizing source it may be necessary that the available voltage between the anode and the cathode of the regenerator tube be as large a proportion of the total anode voltage as possible. The above-mentioned impedance, therefore, limits the degree of stabilization which may be obtained in the previously described arrangement.

It is an object of the invention, therefore, to provide a new and improved self-quench superregenerative receiver which possesses the desirable operating characteristics above enumerated.

It is another object of the invention to provide a new and improved self-quench superregenerative receiver characterized by an exceptionally high stability of operating characteristics over a very wide range of variations of operating conditions to which the receiver is normally subjected during operation.

It is a further object of the invention to provide a self-quench superregenerative receiver having improved amplification or gain yet one which at the same time possesses high stability of its operating characteristics over widely varying conditions of operation to which it is normally subjected in operation.

It is another object of the invention to provide a self-quench superregenerative receiver which is capable of operation at a high quench rate and yet possesses high stability of its operating characteristics over widely varying conditions

of operation to which it is normally subjected in practice.

It is yet another object of the invention to provide a self-quench superregenerative receiver which requires but a relatively low-voltage anode-energizing source yet has an exceptionally high stability of operating characteristics over a very wide range of variations of operating conditions to which the receiver is normally subjected during operation.

In accordance with a particular form of the invention, a self-quench superregenerative receiver comprises a regenerative circuit adapted to have a modulated wave signal applied thereto and including a regenerator tube having anode, cathode, and control electrodes. The receiver also includes an electrical time-constant network coupled to the cathode electrode and having a periodic potential developed thereacross in response to an electrode-current flow of the regenerator tube for effecting periodic self-quenching of the regenerative circuit to provide superregenerative amplification of the applied wave signal. The parameters of the regenerative circuit and the electrical time-constant network are so proportioned that the oscillatory amplitude of the circuit extends to a saturation-level mode of operation thereof during an interval of each quench cycle. The receiver also includes an electrical time-constant network having a time constant longer than that of the first-mentioned network coupled in circuit with the regenerative circuit between the control electrode and the cathode electrode and responsive to control-electrode current of the regenerator tube flowing only during the saturation-level intervals to develop across the second-mentioned network for application to the control electrode a gain-control potential effective to stabilize the operating characteristics of the receiver against operating conditions which tend to modify the average self-quench periodicity of the receiver. The self-quench superregenerative receiver further includes means coupled to a predetermined pair of the aforesaid electrodes for utilizing the modulation components of the applied wave signal derived by the regenerative circuit.

For a better understanding of the present invention, together with other and further objects thereof, reference is had to the following description taken in connection with the accompanying drawing, and its scope will be pointed out in the appended claims.

Referring now to the drawing, Fig. 1 is a circuit diagram, partly schematic, representing a complete self-quench superregenerative receiver embodying the present invention in a particular form; and Fig. 2 comprises graphs utilized in explaining the operation of the receiver.

Referring now more particularly to Fig. 1 of the drawing, the self-quench superregenerative receiver comprises a regenerative circuit 10 including a regenerator tube 11 having an anode, a cathode, and a control electrode. The regenerative circuit 10 includes an input circuit 12 coupled to the control electrode of the tube 11 and shunted by a damping resistor 13. The input circuit 12 is tunable by an adjustable inductor 15 which is coupled to an antenna system 16. The feedback of energy from the output circuit to the input circuit of tube 11 to produce regeneration is provided by a winding 18 included in the cathode circuit of the tube 11 and coupled to the inductor 15. The terminal of the winding 18 opposite its cathode terminal is adapted selectively

to be connected to ground either through a single-pole double-throw switch 20 or through an electrical time-constant network 21 comprising a resistor 23 connected in parallel with a condenser 24. The switch 20 will be referred to as having two operating positions for the switch blade thereof designated *a* and *b* for reasons which will be made more apparent hereinafter. The elements of the network 21 have values so selected that in one of the operating positions of the switch 20, namely the position *b*, the network comprises a self-quench means for developing a voltage thereacross to effect periodic quenching of the regenerative circuit 10 and thereby provide superregenerative amplification of a modulated wave signal applied to the input circuit 12.

The anode of the tube 11 is connected to a source of energizing potential, indicated as +B, through a resistor 22 and a radio-frequency choke coil 14 and is also connected to ground through a condenser 25. The choke coil 14 has a small impedance to signals of quench frequency. The resistor 22 and the condenser 25 are represented as being adjustable in order that it may have somewhat different values depending upon the type of self-quench operation desired for the superregenerative receiver. When anode-quench operation is desired, rather than the cathode-circuit type of quench earlier mentioned, the condenser 25 is quite small so that the potential thereacross may vary sufficiently to provide the proper quench-voltage wave. When the cathode-circuit or control-electrode circuit type of self-quench operation is employed, the condenser 25 has a larger capacitance than with the anode-circuit type of self-quench operation. For the control-electrode type of quench operation presently to be described, the condenser 25 must also be of sufficient size to constitute a by-pass condenser for the modulation components of the applied wave signal when the audio-frequency components of the wave signal applied to the superregenerative receiver are to be derived from the control-electrode circuit of tube 11, as will be described subsequently. However, when the modulation components are taken from the anode circuit of the regenerator tube 11, in a manner also to be described hereinafter, the condenser 25 is somewhat smaller in size so as not to comprise a by-pass condenser for the modulation components. The resistor 22, in each instance, is proportioned to provide self-quench operation for the anode-quench circuit arrangements or to provide the proper energizing potential for the regenerator tube 11 in the cathode or the control-electrode quench arrangements.

The self-quench superregenerative receiver also includes another electrical time-constant network 27 adapted selectively to be included in the control-electrode circuit of the regenerator tube 11 for effecting control-electrode circuit self-quenching. This network comprises a condenser 28, which is connected between one terminal of the tuned input circuit 12 and ground, and a resistor 29. The resistor 29 is connected between the ungrounded terminal of the condenser 28 and a movable blade 30 of a single-pole triple-throw switch 31 through a resistor 32 which may be adjustable. A source of positive bias potential indicated as +B is connected across a voltage divider 33 comprising series-connected resistors 34 and 35. The low-potential, intermediate-potential, and high-potential terminals of the voltage divider 33 are connected, respectively, to stationary switch contacts *a*, *b*, and *c* of the switch 31.

3.1 so that selective movement of the blade 30 thereof will connect the resistor 32 to any desired one of these positions. The condenser 28 and the resistor 29, which together have a time constant such that self-quench action is possible and thus a time constant longer than the time constant of damping of the tuned input circuit 12, have suitable values to provide the desired wave shape for the quench voltage. The resistor 29 preferably has a value of resistance which is much greater than the control electrode-cathode impedance of the regenerator tube 11 during moments when the control electrode is conductive.

The superregenerative receiver further includes another electrical time-constant network 37 which is responsive to the control-electrode current flowing therein during the saturation-level intervals of the receiver to develop and apply to the control electrode of tube 11 a gain-control potential effective to stabilize the operating characteristics of the receiver against operating conditions which tend to modify the average self-quench periodicity of the receiver. This network comprises the resistor 32 and a condenser 38, the latter being connected between the junction of the resistors 29 and 32 and ground. The network 37 has a time constant which may be longer than the average self-quench periodicity of the receiver and also is longer than the time constant of damping of the tuned input circuit 12. However, the time constant of the network 37 may sometimes be less than the duration of one quench period, the limiting condition being that the signal level during one quench period shall affect the control electrode-cathode bias during the next quench cycle. The condenser 38 ordinarily has a sufficiently large capacitance that it has a low impedance for currents of modulation-signal frequencies to prevent a degenerative action with respect thereto, that is, a capacitance sufficiently large that the bias voltage developed thereacross cannot change appreciably with dynamic changes of control-electrode current resulting from dynamic changes of self-quench frequency which in turn are caused by the amplitude modulation of a received wave signal. The condenser 38 preferably has a large value of capacitance when the switch blade 30 is to engage switch contact *a* but may have a considerably smaller value when the switch is to engage either of the switch contacts *b* or *c* for reasons which will become more apparent hereinafter.

The superregenerative receiver further includes means coupled to a self-quench network for deriving the modulation components of a wave signal applied to the tuned input circuit 12. Although this means may be coupled to any of the described self-quench networks, for simplicity only two such coupling arrangements are represented. One arrangement comprises a single-pole double-throw switch 41, the movable blade 42 of which is adapted to be coupled through a stationary switch contact *a* to the anode of the tube 11 or through a second stationary switch contact *b* to a conductor 43 which is connected to a stationary switch contact *c* of a single-pole triple-throw switch 51. The blade 42 of the switch 41 is coupled to the input circuit of a conventional audio-frequency amplifier 45 through a low-pass filter network 44 effective to remove the quench-frequency components appearing in the superregenerative circuit. The output circuit of the amplifier 45 is coupled to a signal-reproducing device 46 of conventional construction. The switch 51 just mentioned includes a movable

blade 52 adapted selectively to engage the aforementioned switch contact *c*, a neutral switch contact *a*, and a switch contact *b* wherein the resistor 29 is short-circuited and the quench-frequency determining action of the network 27 is prevented.

Considering now the operation of the superregenerative receiver just described, it will be assumed initially that switches 20, 31 and 41 are in the positions indicated in the drawing and that switch 51 is operated to close its contact *b*. It will also be assumed that the condenser 25 and the resistor 22 have been adjusted to proper values. For this assumed condition, the receiver operates as a self-quench superregenerative receiver wherein the resistor-condenser network 21 in the cathode circuit of the regenerator tube 11 develops the required self-quench voltage and the modulation components of the applied wave signal are derived from the anode-cathode circuit of the tube 11, amplified in unit 45, and applied to the signal-reproducing device 46. Referring now to the curves of Fig. 2, it will be assumed, for the purpose of analysis, that a new cycle of self-quench operation begins at time t_0 at which time the signal applied to the tuned input circuit 12 from the antenna system 16 begins to build up from the amplitude E represented for the modulated wave signal shown in Fig. 2a. The oscillations in the tuned input circuit 12 are regeneratively amplified and build up in amplitude during the oscillation build-up interval t_0-t_1 , as represented by the solid-line curve A which it may be noted is plotted to a decibel scale on the ordinate axis. The increase of oscillation amplitude continues to a saturation level thereof designated E_s . The oscillations in the input circuit 12 continue approximately at this amplitude level during the saturation-level interval t_1-t_2 of the superregenerative circuit. The duration of the last-mentioned interval is determined by the time required for the network 21 to develop thereacross from the anode-current pulse a bias potential sufficient to bias regenerator tube 11 to anode-current cutoff. In particular, the saturation-level interval is established by the time required for the condenser 24 to charge to the value where it produces anode-current cutoff in tube 11. At time t_2 , the tube 11 is biased to cutoff and the amplitude of the oscillations in the tuned circuit 12 decreases exponentially to reach at time t_3 their original amplitude E as shown by curve A. As soon as the tube 11 becomes nonconductive at time t_2 , the condenser 24 of the network 21 begins to discharge through the resistor 23. The duration of the discharge interval t_2-t_4 is established by the time required for the condenser 24 to discharge sufficiently to permit the regenerator tube 11 again to become conductive and initiate a new cycle of operation similar to that just described.

The envelope of the oscillations developed in the tuned circuit 12 during the cycle of operation just described is represented by the solid-line curve B of Fig. 2b. The anode-current flow through tube 11 is of somewhat irregular pulse wave form as represented by the solid-line curve C of Fig. 2c. It will be noted that the anode-current pulse comprises a first portion P_1 of relatively low amplitude which occurs during the build-up interval t_0-t_1 and a second portion P_2 of relatively large amplitude occurring during the saturation-level interval t_1-t_2 . During the last-mentioned interval, the control electrode of tube 11 becomes conductive and the resulting control

electrode-cathode rectification of the oscillations developed in the input circuit 12 takes place. A roughly symmetrical control-electrode current pulse is thereby produced, as represented by the solid-line curve D of Fig. 2d. Although the duration of the pulse is very slightly shorter than that of the second portion P_2 of the anode-current pulse C, the control-electrode current pulse is represented as having a duration corresponding substantially thereto to simplify the illustration.

It will be clear from the above-described operation that the self-quench period of the superregenerative receiver comprises the sum of the oscillatory build-up interval t_0-t_1 , the saturation-level interval t_1-t_2 , and the discharge interval t_2-t_4 . It will be manifest that if any one of these three intervals changes, the quench period varies accordingly. The saturation level of the superregenerative circuit has an approximately constant value, since it is established by the receiver parameters, and thus determines the amplitude of each pulse of anode current. The saturation-level interval t_1-t_2 may be considered as approximately constant in duration since it is established by a constant amplitude anode-current pulse and by the time required for the cathode-circuit condenser 24 of constant capacitance to charge. The discharge interval t_2-t_4 is effectively constant since it is determined by the discharge time constant of the condenser 24 and the resistor 23 of the self-quench network 21. Consequently, as a first order approximation, the quench period can be considered to vary only with a change in the build-up interval t_0-t_1 . In a conventional self-quench superregenerative circuit, the build-up interval effectively becomes shorter with increasing amplitude of the applied wave signal. This is because the oscillations in the tuned input circuit have an increasingly larger initial amplitude so that smaller intervals of time are required for the amplitude of the oscillations to build up to the saturation-level value. For example, if it be assumed that in a conventional self-quench superregenerative circuit the amplitude of the applied wave signal has a larger value E' , as indicated in Fig. 2a, the oscillatory build-up interval is shortened to the new value t_0-t_1' . This in turn causes the termination of the saturation-level interval to be advanced to the moment t_2' and also the termination of the discharge interval to be advanced to the moment t_4' . Accordingly the increased amplitude of the applied wave signal causes the self-quench period of a conventional self-quench superregenerative circuit to be decreased from its initial value t_0-t_4 to a new value t_0-t_4' .

Under the assumed conditions last mentioned, namely that the regenerative circuit 10 operates as a conventional self-quench superregenerative circuit and has a larger amplitude wave signal applied thereto, the manner of the oscillation build-up in the tuned input circuit 12 for a wave signal having the amplitude E' is now represented by the broken-line curve A' of Fig. 2, the amplitude envelope of the oscillations by the broken-line curve B', and the anode current and the control-electrode current of the regenerator tube 11 by the respective broken-line curves C' and D'. Thus in a conventional self-quench type of superregenerative receiver, the quench period decreases with increasing wave-signal amplitude. This decreasing quench period, which corresponds to an increasing quench frequency, causes the average value of the anode current and the

average value of the control-electrode current of the receiver to increase since there are developed a greater number of current pulses in a given time interval. It will be observed that the anode-current pulse C' has a wave form different from that of the pulse C by virtue of the fact that the first portion P₁' of the pulse C' has decreased in duration. Consequently the average value of the anode current of the regenerator tube 11 has not increased in direct proportion to the increase in the quench frequency. However, the average control-electrode current has increased in direct proportion to the change in the quench frequency due to the similar wave form of pulses D and D'.

Consider now the effect of the resistor-condenser network 37 on the operation of the superregenerative circuit of the present invention when the oscillation amplitude of the applied wave signal has increased to the value E'. The input-circuit oscillation amplitude initially tends to increase in the manner represented by curve A' of Fig. 2a, thereby shortening the quench period and increasing the control-electrode current. The condenser 38 thereupon tends to charge more quickly over a period of one or more but usually several quench cycles by virtue of the increase in the average value of the control-electrode current. In doing so, the condenser 38 develops a larger negative bias for application to the control electrode of the regenerator tube 11. This larger value of bias potential decreases the transconductance of the tube 11, which in turn decreases the value of the negative conductance developed in the tuned input circuit 12. As a result, the oscillations in the tuned input circuit build up more slowly in amplitude, as represented by the dot-and-dash curve A'' of Fig. 2a. This causes the build-up interval t₀-t₁ of the superregenerative circuit to be substantially the same for an applied wave signal of amplitude E' as for a wave signal of amplitude E. Solid-line curve B therefore approximately represents the amplitude envelope of the oscillations developed in the tuned input circuit 12 for both a wave signal of amplitude E and for one of amplitude E'. Similarly the solid-line curve D approximately represents the wave form of the control-electrode current pulses of the tube 11 for applied wave signals having amplitudes E and E'. The dotted-line curve C'' represents the wave form of the anode-current pulse for an input signal having the amplitude E'. It will be seen that the current pulse during the saturation-level interval is approximately identical with that obtained with an input signal of amplitude E. However, the initial portion P'' of the anode-current pulse represented by curve C'' has a somewhat lower amplitude value than the corresponding portion P₁ of the pulse of curve C. Thus the electrical time-constant network 37, which is responsive to control-electrode current flowing therein only during the saturation-level intervals of the regenerative circuit, develops and applies to the control electrode of the regenerator tube 11 a gain-control potential which is effective to stabilize the operating characteristics of the receiver against changes in the average amplitude of the applied wave signal which tend to modify the average self-quench periodicity of the receiver.

By similar analysis it may be shown that the network 37 is effective to control the operation of the self-quench superregenerative receiver so that the average control-electrode current and the average self-quench frequency are maintained substantially constant with variations of other

operating conditions to which the receiver is normally subjected in operation. The gain-control potential developed by the network 37 thus stabilizes the regenerative circuit 10 for such operating conditions as variations of the transconductance of the regenerator tube 11 due to aging, changes in the loading of the tuned input circuit 12 due to the antenna system 16, variations of the anode-energizing potential +B, and reduces variations in operating characteristics in different radio receivers due to some component tolerances.

The position of the blade 30 of the switch 31 may be adjusted in a manner to determine the degree of stabilization of the operating characteristics of the superregenerative receiver which may be effected by the action of the network 37. Progressively greater stabilization may be realized when the switch 31 is set to close one of the switch contacts a, b, or c, in the order named. Greater stability against conditions which tend to modify the average self-quench periodicity of the receiver is provided with the switch 31 closed to its contact c and with the resistor 32 increased in value sufficiently to produce the same quench rate since, for a given change in the average control-electrode current of tube 11, a greater change in the gain-control potential available at the control electrode is realized for providing the stabilizing action. For many purposes satisfactory stabilization may be realized with the switch 31 operated to close its contacts a or b.

Although the network 37 is effective to stabilize the operating characteristics of the receiver against operating conditions which tend to modify the average self-quench periodicity of the receiver, the self-quench period thereof may vary dynamically in accordance with the amplitude modulation of the received amplitude-modulated wave signal due to the low impedance of the condenser 38, at frequencies corresponding to those of the modulation components, with respect to the value of the resistor 32, and the value of the control electrode to cathode impedance of the tube 11. Thus the dynamic quench rate varies in accordance with the amplitude modulation of the received wave signal and the modulation components are derived in the anode circuit of the regenerator tube 11 as dynamic variations of its anode current.

Essentially similar operation of the superregenerative receiver is realized when the self-quench network therefor is positioned in the anode circuit of the regenerator tube 11 instead of in the cathode circuit thereof. This type of self-quench operation may be realized by adjusting condenser 25 so that its capacitance is quite small, by moving the switch 20 to close its contact a, and by leaving the remaining switches in the positions which were previously mentioned. The condenser 25 and the resistor 22 now determine the quench-voltage wave shape since the condenser 25 discharges through the anode to cathode space path of the regenerator tube 11 until the anode voltage drops to a level where space current ceases to flow, whereupon the condenser 25 charges through the resistor 22 from the energizing source +B. Thus the periodic charging and discharging of the condenser 25 determines the quench-voltage wave shape. When the condenser 25 and the resistor 22 in the anode circuit of the tube 11 comprise the quench determining elements for the superregenerative circuit, a large output signal with respect to the modulation-signal components of the applied

wave signal may be realized. This results because there is no degeneration with respect to the modulation-signal components in the anode circuit of the tube 11 and because of the large impedance and the large current flow in the anode circuit. No degeneration takes place with this type of quench circuit because the stabilizing network may be chosen to present an impedance to audio-frequency components so low that it does not tend to stabilize with respect to audio-frequency variations in the quench rate.

When the superregenerative receiver is to be operated with both the quench determining network and the stabilizing network in the control electrode-cathode circuit of the regenerator tube 11, the condenser 25 is adjusted to provide a relatively large capacitance as mentioned hereinbefore, the switch 20 is operated to close its contact *a*, the switch 41 may be set to close either of its contacts *a* or *b* depending on whether the modulation components of the applied signal are to be derived from the anode circuit or the control-electrode circuit of the regenerator tube, and the switch 51 is adjusted to close its contact *a* or its contact *c* as required. As previously mentioned, switch 31 may be operated to close its contact *c* for providing a maximum stabilizing action with respect to the operating characteristics of the receiver. When the various switches are positioned as last mentioned, the network 37 effectively comprises the stabilizing network while the network 27 comprises a network for developing from the control-electrode current pulses the self-quench voltage for the receiver. The operation of the receiver when connected in this manner is much the same as that which was previously described in detail, and hence will not be repeated. Because the resistor 29 has a high value and is effectively in series with the control electrode-cathode impedance of the tube 11 with respect to the flow of control-electrode current, the condenser 38 may have a relatively small value of capacitance and yet provide with the resistor 32 the necessary stabilizing action. For the anode and the cathode types of self-quenching previously described, the condenser 38 has a relatively large value of capacitance so that an electrolytic type condenser is ordinarily employed. However, when the self-quenching action is provided by the network 27, an economy may be effected because of the relatively smaller capacitance value of the condenser 38. When the switch 51 is adjusted to close its contact *c* and the switch blade 42 is moved to close its contact *b*, the modulation components of the applied wave signal are derived from the quench-frequency determining network 27 for application to the amplifier 45. This offers the advantage of good audio-frequency output since no degeneration with respect to audio-frequency components appears at network 27 if the condenser 25 is increased in value to represent a low impedance at modulation frequencies, although the output signal is not as large as when it is taken from the anode of tube 11.

Under certain limiting conditions self-quench superregenerative receivers embodying the present invention offer certain advantages over self-quench superregenerative receivers of the type disclosed in the above-mentioned application of Bernard D. Loughlin in which stabilization of the receiver operating characteristics is accomplished by a resistor-condenser network in the cathode circuit of the regenerator tube. A stabilizing network in the cathode circuit of the regenerator

tube reduces the effective energizing potential applied between the anode and the cathode electrodes of the tube, thus reducing the maximum available transconductance thereof. When it is necessary to employ high-quench frequencies, improved operation results when the transconductance of the regenerator tube is high. In a typical design employing cathode-stabilizing elements of the type just mentioned, the stabilizing elements reduce the anode-cathode voltage applied to the regenerator tube by approximately 20 per cent., thus under conditions of limited available anode-energizing potential this reduction in the anode-cathode voltage may appreciably affect the over-all operation. Since the average control-electrode current of the self-quench superregenerative receiver is directly proportional to the quench rate thereof, it will be manifest that a self-quench superregenerative receiver embodying the present invention provides somewhat more effective stabilization of the operating characteristics against changes in the operating conditions than has heretofore been obtainable in prior such receivers. The greater stability thereof may afford more flexibility in the choice of the wave shape of the quench voltage when particular operating characteristics of the receiver are desired to be obtained therefrom. A saving in the cost of the components for use in the stabilization network of the superregenerative receiver may also be effected, since condensers of relatively smaller capacitance may be employed in lieu of the somewhat more expensive electrolytic condensers employed in prior stabilized self-quench superregenerative receivers. Furthermore, a self-quench superregenerative receiver embodying the instant invention is suited for use at higher quench rates since the regenerator tube is operating in such a manner that the transconductance thereof is not undesirably reduced by a low anode-cathode voltage on the regenerator tube.

While applicant does not intend to limit the invention to any particular design constants, the following values are appropriate for a particular embodiment of the invention.

Resonant frequency of

tuned input circuit	21.75 megacycles
Condenser 24	2500 micromicrofarads
Condenser 25:	
Cathode quench	0.01 microfarad
Anode quench	300 micromicrofarads
Control-electrode	
quench	0.01 microfarad
Condenser 28	500 micromicrofarads
Condenser 38	10 microfarads
Resistor 13	15 kilohms
Resistor 22:	
Cathode quench	22 kilohms
Anode quench	33 kilohms
Control-electrode	
quench	22 kilohms
Resistor 23	1.5 kilohms
Resistor 29	6.8 kilohms
Resistor 32	500 kilohms (maximum)
Resistor 34	47 kilohms
Resistor 35	47 kilohms
Tube 11	Type 12AT7
+B	100 volts
Approximate quench frequency	30 kilocycles

While there has been described what is at present considered to be the preferred embodiment

of this invention, it will be obvious to those skilled in the art that various changes and modifications may be made therein without departing from the invention, and it is, therefore, aimed to cover all such changes and modifications as fall within the true spirit and scope of the invention.

What is claimed is:

1. A self-quench superregenerative receiver comprising: a regenerative circuit adapted to have a modulated wave signal applied thereto and including a regenerator tube having anode, cathode, and control electrodes; self-quench means coupled to said cathode electrode and having a periodic potential developed thereacross in response to an electrode-current flow of said regenerator tube for effecting periodic self-quenching of said regenerative circuit to provide superregenerative amplification of said applied wave signal; the parameters of said circuit and said self-quench means being so proportioned that the oscillatory amplitude of said circuit extends to a saturation-level mode of operation thereof during an interval of each quench cycle; an electrical time-constant network, having a time constant longer than that of said self-quench means and the periodicity of the lowest frequency modulation components of said applied wave signal, coupled in circuit with said regenerative circuit between said control electrode and cathode and responsive to control-electrode current of said regenerator tube flowing only during said saturation-level intervals to develop across said network for application to said control electrode a gain-control potential effective to stabilize the operating characteristics of said receiver against operating conditions which tend to modify the average self-quench periodicity of said receiver; and means coupled to said self-quench means for utilizing the modulation components of said applied wave signal derived thereby.

2. A self-quench superregenerative receiver comprising: a regenerative circuit adapted to have a modulated wave signal applied thereto and including a regenerator tube having an anode, a cathode and a control electrode; self-quench means coupled between said cathode and a fixed potential point and having a periodic potential developed thereacross in response to the anode-cathode current flow of said regenerator tube for effecting periodic self-quenching of said regenerative circuit to provide superregenerative amplification of said applied wave signal; the parameters of said circuit and said self-quench means being so proportioned that the oscillatory amplitude of said circuit extends to a saturation-level mode of operation thereof during an interval of each quench cycle; an electrical time-constant network, having a time constant longer than that of said self-quench means and the periodicity of the lowest frequency modulation components of said applied wave signal, coupled in circuit with said regenerative circuit between said control electrode and cathode and responsive to control-electrode current of said regenerator tube flowing only during said saturation-level intervals to develop across said network for application to said control electrode a gain-control potential effective to stabilize the operating characteristics of said receiver against operating conditions which tend to modify the average self-quench periodicity of said receiver; and means coupled to said anode and said cathode for

utilizing the high-amplitude modulation components of said applied wave signal derived by said self-quench means.

3. A self-quench superregenerative receiver comprising: a regenerative circuit adapted to have a modulated wave signal applied thereto and including a regenerator tube having anode, cathode, and control electrodes; an electrical time-constant network coupled to said cathode electrode and having a periodic potential developed thereacross in response to an electrode-current flow of said regenerator tube for effecting periodic self-quenching of said regenerative circuit to provide superregenerative amplification of said applied wave signal; the parameters of said circuit and said network being so proportioned that the oscillatory amplitude of said circuit extends to a saturation-level mode of operation thereof during an interval of each quench cycle; an electrical time-constant network having a time constant longer than that of said first-mentioned network coupled in circuit with said regenerative circuit between said control electrode and cathode electrode and responsive to control-electrode current of said regenerator tube flowing only during said saturation-level intervals to develop across said second-mentioned network for application to said control electrode a gain-control potential effective to stabilize the operating characteristics of said receiver against operating conditions which tend to modify the average self-quench periodicity of said receiver; and means coupled to a predetermined pair of said electrodes for utilizing the modulation components of said applied wave signal derived by said regenerative circuit.

4. A self-quench superregenerative receiver comprising: a regenerative circuit adapted to have a modulated wave signal applied thereto and including a regenerator tube having an anode, a cathode, and a control electrode; a resistor and a condenser connected in parallel therewith coupled to said cathode and having a periodic potential developed thereacross in response to cathode-current flow of said regenerator tube for effecting periodic self-quenching of said regenerative circuit to provide superregenerative amplification of said applied wave signal; the parameters of said circuit and said resistor and condenser being so proportioned that the oscillatory amplitude of said circuit extends to a saturation-level mode of operation thereof during an interval of each quench cycle; an electrical time-constant network having a time constant longer than that of said resistor and said condenser coupled in circuit with said regenerative circuit between said control electrode and cathode and responsive to control-electrode current of said regenerator tube flowing only during said saturation-level intervals to develop across said network for application to said control electrode a gain-control potential effective to stabilize the operating characteristics of said receiver against operating conditions which tend to modify the average self-quench periodicity of said receiver; and means coupled to said anode and said cathode for utilizing the modulation components of said applied wave signal derived by said regenerative circuit.

5. A self-quench superregenerative receiver comprising: a regenerative circuit adapted to have a modulated wave signal applied thereto and including an oscillatory circuit and a regenerator tube having an anode, a control electrode and a cathode coupled to said oscillatory circuit;

a parallel-connected resistor-condenser network having a time constant greater than the time constant of damping of said oscillatory circuit and coupled to said cathode and having a periodic potential developed thereacross in response to an electrode-current flow of said regenerator tube for effecting periodic self-quenching of said regenerative circuit to provide superregenerative amplification of said applied wave signal; the parameters of said regenerative circuit and said network being so proportioned that the oscillatory amplitude of said circuit extends to a saturation-level mode of operation thereof during an interval of each quench cycle; an electrical time-constant network having a time constant longer than that of said first-mentioned network coupled in circuit with said regenerative circuit between said control electrode and cathode and responsive to control-electrode current of said regenerator tube flowing only during said saturation-level intervals to develop across said network for application to said control electrode a gain-control potential effective to stabilize the operating characteristics of said receiver against operating conditions which tend to modify the average self-quench periodicity of said receiver; and means coupled to said regenerative circuit for utilizing the modulation components of said applied wave signal derived by said regenerative circuit.

6. A self-quench superregenerative receiver comprising: a regenerative circuit adapted to have a modulated wave signal applied thereto and including an oscillatory circuit and a regenerator tube having an anode, a control electrode and a cathode coupled to said oscillatory circuit; an electrical time-constant network, having a time constant greater than the time constant of damping of said oscillatory circuit and including a resistor having a value of resistance much greater than the conductive control electrode-cathode resistance of said tube, coupled between said cathode and a fixed poten-

tial point and having a periodic potential developed thereacross in response to an electrode-current flow of said regenerator tube for effecting periodic self-quenching of said regenerative circuit to provide superregenerative amplification of said applied wave signal; the parameters of said regenerative circuit and said network being so proportioned that the oscillatory amplitude of said circuit extends to a saturation-level mode of operation thereof during an interval of each quench cycle; a source of positive bias potential; and an electrical time-constant network having a time constant long with respect to that of said first-mentioned network, including a condenser having a relatively small value of capacitance, coupled in circuit with said regenerative circuit between said control electrode and said fixed potential point and to said potential source and responsive to control-electrode current flowing therein only during saturation-level intervals to develop across said second-mentioned network for application between said control electrode and said cathode a gain-control potential effective to stabilize the operating characteristics of said receiver against operating conditions which tend to modify the average self-quench periodicity of said receiver.
